UNITED STATES PATENT OFFICE.

WILLIAM LESLIE ROSS, OF EDINBURGH, SCOTLAND.

GRINDER FOR COMMUTATORS OR DISTRIBUTERS OF MOTOR-CAR ENGINES.

1,188,837.

Specification of Letters Patent. Patented June 27, 1916.

Application filed September 21, 1915. Serial No. 51,811.

To all whom it may concern:

Be it known that I, WILLIAM LESLIE ROSS, of 33 Ivy Terrace, Edinburgh, Scotland, motor mechanic, have invented certain new and useful Improved Grinders for Commutators or Distributors of Motor-Car Engines, of which the following is a specification.

This invention relates to improved grinders for commutators or distributors of motor car engines, and has for its object to simplify and cheapen the construction of such and to obtain effective working of the apparatus.

According to my invention, the grinder consists of a carborundum, emery, or other suitable wheel or disk having a shaft passing through the center thereof and into and through a bush forming a part of a box-like bracket and which shaft is provided with suitable teeth which gear with the teeth on a gear wheel carried inside of the box-like bracket. Also carried on the above shaft there is a holder or chuck in which the commutator or distributor is held. This holder is provided on its outer periphery with teeth which gear with teeth at the end of the driving shaft which passes through the box-like bracket. Means are also provided on the box-like bracket for fixing or clamping the device to a suitable bench, table, or other fixture, the power being supplied by either hand or foot movement. A suitable arrangement is provided for adjusting the commutator or distributor in order to bring it into contact with the carborundum, emery, or other wheel or disk. I may also provide a metal strap to retain the commutator or distributor in position when being operated upon. This metal strap passes over the outside of the commutator and has each end thereof suitably fixed to the holder or chuck.

When the worn commutator or distributor is placed in position and the proper adjustment made, the power is applied when the grinding and facing is effected by the grinder coming into contact with the worn parts. I may also slightly vary the gear for operating the chuck or holder, so that it may be made to revolve in the opposite direction to that of the grinder.

In order that my invention may be properly understood and readily carried into effect, I have hereunto appended one sheet of drawings of which,

Figure 1 is an elevation of the apparatus embodying my invention. Fig. 2 is a side elevation, and Fig. 3 is a transverse vertical

section of the same. Fig. 4 is a similar view to Fig. 3 illustrating in part a modified form of the apparatus, and Fig. 5 is a plan of part of the same, all hereafter more fully referred to and described.

A is the box-like bracket through the center of which passes the driving shaft or spindle B. To one end of the shaft or spindle B is mounted the crank hand lever C for actuating the mechanism; to the other end of the said shaft or spindle is mounted a tooth pinion D which engages with a tooth wheel E being in one piece with the external body of the holder or chuck F or formed separate and suitably connected thereto. Mounted coaxially on the shaft or spindle B is a tooth wheel G, contained within the box-like bracket A. The said tooth wheel engages with a tooth pinion H mounted on and giving motion to a shaft I parallel to the shaft or spindle B. Upon the end of the shaft I is mounted the grinding wheel or disk J composed of carborundum, emery, or other such like composition. The commutator or distributor K to be treated or ground is carried within the outer wall f of the holder or chuck F, and revolves with the chuck or holder during the grinding operation. The holder or chuck F and the grinding wheel or disk J revolve in the same direction but as seen the wheel or disk revolves at a much greater speed.

The chuck or holder F is capable of some lateral play or adjustment in order to present the surface of the commutator to the correct position to be acted upon by the grinding wheel J. This is effected by the right and left handed thumb screw L, screwed into the snug or projection M formed on the outer wall of the box-like bracket A and engaging the pap or projection N formed on the sleeve or bush E¹ carrying the said chuck or holder F. The sleeve or bush E¹ is connected to the sleeve or bush E² encircling the outer end of the driving shaft or spindle B by a distance piece E³.

The box-like bracket A containing the tooth wheel G and tooth pinion H is composed of two parts having snugs A¹, A², A³ formed around the circumference. The two parts are connected together by screws A⁴, A⁵, A⁶. The apparatus is clamped in position to any desired place required for use between the jaws O, P, Q, by means of the thumb screw R.

Referring to Fig. 4 it will be seen that between the tooth wheel E and the tooth pinion D is interposed a tooth wheel S. The object of this arrangement is to cause the 5 chuck or holder F to revolve in the opposite direction to that of the grinding wheel or disk J.

The device for giving the adjustment differs slightly in the arrangement shown in 10 Fig. 5; the thread of the adjusting screw L works through a bolt T bolted to one of the sections of the box-like bracket, while the other thread of the screw works through the fork U connected to the extension E¹ supporting the holder or chuck F.

Claims.

1. In an apparatus for grinding commutators or distributors of motor car engines, a box-like bracket, a driving shaft or spindle passing through the center of said bracket, a holder or chuck carried by said shaft, a crank operating lever mounted on one end of said shaft or spindle, a toothed pinion mounted at the other end of said 20 shaft or spindle, a toothed wheel engaging with said pinion for giving motion to said holder or chuck, a toothed wheel coaxially mounted on said driving shaft or spindle, a shaft parallel to said driving shaft, a toothed pinion mounted on said last named shaft 25 engaging with said toothed wheel, both, wheel and pinion being contained in said box-like bracket, a grinding wheel or disk mounted at the end of said parallel shaft 30 and being in contact with the device under treatment, and means for clamping the apparatus in position, substantially as described and for the purpose set forth.

2. In an apparatus for grinding commutators or distributors of motor car engines, a box-like bracket, a driving shaft or spindle passing through the center of said bracket, a holder or chuck carried by said shaft, a crank operating lever mounted on 40 one end of said shaft or spindle, a toothed pinion mounted at the other end of said shaft or spindle, a toothed wheel engaging with said pinion for giving motion to said holder or chuck, a toothed wheel coaxially mounted on the driving shaft or spindle, a shaft parallel to the driving shaft, a toothed 45 pinion mounted on said last named shaft engaging with said toothed wheel, both, wheel and pinion being contained in said box-like bracket, a grinding wheel or disk mounted at the end of said parallel shaft 50 and being in contact with the device under treatment, and means for clamping the apparatus in position, substantially as described and for the purpose set forth.

pinion mounted on said last named shaft engaging with said toothed wheel, both, wheel and pinion contained in said box-like bracket, a grinding wheel or disk mounted 55 on the end of said parallel shaft and in contact with the device under treatment, an intermediate toothed pinion interposed between the toothed wheel of the chuck and the pinion for causing the chuck or holder to revolve in the opposite direction to that of the grinder, substantially as described and for the purpose set forth.

3. In an apparatus for grinding commutators or distributors for motor car engines, a box-like bracket, a driving shaft or spindle passing through the center of said bracket, a holder or chuck carried by said shaft, a toothed pinion mounted at the other end of said shaft or spindle, a toothed wheel 60 engaging with said spindle for giving motion to said holder or chuck, a toothed wheel mounted coaxially on the driving shaft or spindle, a shaft parallel to the driving shaft, a toothed pinion mounted on said last named 65 shaft engaging with said toothed wheel, both, wheel and pinion being contained in said box-like bracket, a grinding wheel or disk mounted at the end of said parallel shaft and in contact with the device under treatment, an intermediate toothed pinion interposed between the toothed wheel of the 70 chuck and the pinion for causing chuck or holder to revolve in the opposite direction to that of the grinder, a thumb clamping screw 75 having a right and left hand screw thread, one thread of said screw working through a snug in the wall of the box-like bracket and the other thread working in an extension 80 forming part of the support on which holder or chuck are carried for adjusting the position of the grinding wheel or disk in relation to the commutator or distributor to be ground, substantially as described and for the purpose set forth.

In testimony whereof I affix my signature in presence of two witnesses.

WILLIAM LESLIE ROSS.

Witnesses:

JOHN LIDDLE,
JOHN TRAIN LIDDLE.
